SPANNER WRENCH OR SIMILAR ARTICLE

Lucian W. Gaskins, 4425 Sandy Lane Road,
Columbus, Ohio

Filed Jan. 28, 1964, Ser. No. 78,395

Term of patent 14 years

(Cl. D54—16)

FIG. 1 is a side elevational view of a spanner wrench or similar article, showing my new design;

FIG. 2 is an end elevational view; and

FIG. 3 is a perspective view thereof.

The side of the spanner wrench or similar article opposite that shown in FIGS. 1 and 3 is a mirror image thereof.

I claim:

The ornamental design for a spanner wrench or similar article, substantially as shown and described.
